CLOTHES WRINGER

George J. Filia, Bridgeport, Conn., assignor to
General Electric Company, a corporation of
New York

Application July 15, 1938, Serial No. 219,387

5 Claims. (Cl. 68—262)

The present invention relates to clothes wringers of the type suitable for use with domestic washing machines.

The object of my invention is to provide an improved construction and arrangement in clothes wringers, and for a consideration of what I believe to be novel and my invention, attention is directed to the following description and the claims appended thereto.

10 In the accompanying drawings, Fig. 1 is a front elevation of a wringer embodying my invention; Fig. 2 is an enlarged front elevation partly in section showing the wringer mechanism; Fig. 3 is a sectional view taken on line 3—3 of Fig. 2; Fig. 4 is a sectional view taken on line 4—4 of Fig. 2; Fig. 5 is a sectional view taken on line 5—5 of Fig. 2; Fig. 6 is an exploded view of one end of the control bar and the associated parts; and Figs. 7, 8 and 9 are views showing the 15 position of the control bar during the operation of the wringer.

Referring to the drawings, there is shown a wringer having a frame comprising side stiles 1 and 2 connected by a bottom frame member 3 which is bolted to the under side of the side stiles. The side stile 1 is integral with a frame supporting the driving mechanism for the wringer and having a depending tubular sleeve 4 which rotatably fits over the upper end of the wringer post 5 of a domestic washing machine and supports the wringer thereon. At the lower end of the sleeve 4 is a flange 6 which rests on a collar 7 fixed to the wringer post 5. The collar 7 has a series of openings 8 which cooperate with the lower end of a detent pin 9 to hold the wringer in one of a plurality of fixed positions. The pin 9 is slidable in a recess 10 in the sleeve 4. It is biased into engagement with the openings 8 by means of a coil spring 11 arranged between the bottom of the recess 10 and the upper end of the pin. The pin is lifted out of engagement with the openings 8 by means of a handle 12 which projects to the outside of the wringer through a slot 13. Movement of the pin 9 is limited by engagement of the handle with the upper and lower edges of the slot.

The wringer is driven by a vertical shaft 14 which is journaled in a bearing 15 at the upper end of the wringer post 5 and which is rotated by any suitable means, for example the driving mechanism for the washing machine. The upper end of the shaft 14 projects beyond the upper end of the wringer post 5 and fixed thereon is a coupling member comprising a collar 16 having 55 diametrically opposite pin-like projections 17

which fit in slots 18 in the lower end of a tubular coupling member 19. The upper end of the coupling member 19 telescopes over the lower end of a stub shaft 20 which is journaled in a bearing 21 carried in a tubular portion 22 integral with the side stile 1 and forming a continuation of the sleeve 4. The lower end of the shaft 20 is coupled to the coupling member 19 by means of a pin 23 fixed to the coupling member 19 and fitting in a slot 24 in the lower end of the shaft 20. 10 The above described arrangement provides a coupling between the shaft 14 and the shaft 20 which does not require accurate alignment.

On the upper end of the shaft 20 is fixed a bevel gear 25 which meshes at all times with bevel gears 26 and 27 rotatably carried on a splined shaft 28. Between the bevel gear 25 and the upper end of the bearing 21 is a thrust washer 29. The left end of the splined shaft 28 is journaled in a bearing 30 carried on an arm 31 integral with the side stile 1. The right end of the shaft 28 has a cylindrical coupling member 32 pinned thereto which rotates in a bearing 33 carried in a boss 34 in the side stile 1. The bearing 33 therefore serves as a support for the right 20 end of the shaft 28.

15 The gears 26 and 27 are rotated in opposite directions by the gear 25. The direction of rotation of the shaft 28 can, therefore, be reversed by selectively connecting one or the other of the gears 26 and 27 to the shaft. This is effected by means of a slidible clutch member 35 splined on the shaft 28. On opposite sides, the clutch member is provided with teeth 36 (shown only on the side facing gear 27) which cooperate with recesses 37 in the gears 26 and 27 to couple one of the gears to the shaft 28. In the position shown in Fig. 2 the clutch member 35 is in the neutral position in which the shaft 28 is stationary. The clutch member 35 is moved to the left or right 30 along the shaft 28 to the coupling positions by means of a tongue 38 which fits in an annular groove 39 in the clutch member. The tongue 38 is fixed to the under side of a channel-shaped shifting lever 40 which is slidable on bosses 41 and 42. The sliding movement of the shift lever 40 is limited by a pin 43 fixed in the boss 41 and projected through an elongated slot 44 in the lever 40. The left end of the lever 40 is held against the boss 41 by means of a washer 45 fixed 40 to the projecting end of the pin 43. At the right end of the shifting lever 40 is a cylindrical pin-like projection 46 which slidably fits in a channel formed by the depending side walls 47 of a lever 48. Integral with the upper side of the lever 48 55

45 The wringer is driven by a vertical shaft 14 which is journaled in a bearing 15 at the upper end of the wringer post 5 and which is rotated by any suitable means, for example the driving mechanism for the washing machine. The upper end of the shaft 14 projects beyond the upper end of the wringer post 5 and fixed thereon is a coupling member comprising a collar 16 having 50 diametrically opposite pin-like projections 17

is a pin 49 by means of which the lever 48 is pivoted on a bracket 50 fixed to a member 51 slidably carried in a slot 52 (Fig. 5) in the side stile 1. The member 51 is moved in the slot 52 by a projection 53. The bracket 50 and the projection 53 project beyond the edges of the slot 52 on opposite sides of the side stile and therefore serve to hold the member 51 in the slot. The lever 48 is biased to the position shown in Fig. 3 by means of a tension spring 54 arranged between one end of the lever 48 and hook 55 fixed to the arm 31. The spring 54 biases the other end of the lever 48 against the bracket 50, as shown in Fig. 3.

15 When the parts are in the position shown in Fig. 3 the projection 46 on the shifting lever 40 is directly below the pin 49 on the lever 48. In this position the clutch member 35 is in the neutral position in which neither of the gears 26 or 20 27 is connected to the shaft 28.

When the member 51 is moved toward the left in the slot 52 (downward as viewed in Fig. 3) the lever 48 is moved to a position in which the projection 46 assumes the position with reference 25 to the lever 48 indicated by reference numeral 56 in Fig. 3. During this movement, a force will be exerted on the shifting member 40 tending to move the lever 40 to the left, as viewed in Fig. 3, and there will therefore be an equal and opposite 30 force of reaction exerted on the lever 48 which will be toward the right, as viewed in Fig. 3. Under normal conditions, this force will be less than the force exerted by the tension spring 54 and the sole effect will be that the clutch member 35 is moved into engagement with the gear 26 35 coupling this gear to the shaft 28.

Under some circumstances, the clutch teeth 36 will strike the portions of the gear 26 intermediate the depressions 37, and under these circumstances, further movement of the clutch member toward the engaged position would be impossible. Under these circumstances, the force of reaction exerted on the lever 48 by means of the projection 46 will be of sufficient magnitude 45 to overcome the force of the spring 54 and the lever 48 will accordingly be pivoted about the pin 49 relieving the pressure exerted on the shifting lever 40 and preventing damage to the shifting mechanism. The gear 26 is rotating 50 continuously so that the condition in which the clutch teeth 36 are opposite the portions of the gear intermediate the depressions 37 will be momentary and will be corrected by the rotation of the gear 26. As soon as the depressions 37 of 55 the gear 26 are rotated to a position opposite the clutch teeth 36 the lever 48 will be returned by the spring 54 to the position shown in Fig. 3 thereby completing the movement of the shifting lever 40 necessary to move the clutch member 35 to the engaged position. From the above description, it is clear that the clutch member 35 is 60 yieldingly moved to the engaged position with the gear 26.

When the member 51 is moved from the position 65 in which the clutch member 35 is engaged with the gear 26 the lever 48 exerts a force on the pin 46 tending to move the shifting member 40 to the right, as viewed in Fig. 3. There is, therefore, an equal and opposite force of reaction exerted 70 on the lever 48 acting toward the left. This force will tend to pivot the lever 48 in a counter-clockwise direction, as viewed in Fig. 3, and will therefore hold the lever 48 solidly in the position shown in Fig. 3. There is, therefore, no yielding 75 movement of the lever 48 while the clutch mem-

ber 35 is being moved from the engaged position.

By a similar analysis, it will be found that the clutch member 35 is yieldably moved into engagement with the gear 27 and is positively moved from the engaged position. It is obviously desirable that the clutch member be yieldingly moved into engagement with the gears so as to prevent damage to the mechanism in case the teeth of the clutch member are not properly aligned with the cooperating parts of the gears. 10 However, since there is a possibility that the clutch member may stick in the engaged position, particularly when the clutch member is shifted under heavy load, it is equally desirable that the clutch member be moved from the engaged position positively. Both of these objects are fulfilled in the above described mechanism. 15

The driving mechanism is enclosed by a shell 57 which is secured to the side stile 1 by means of screws 58. The shell 57 has a skirt 59 depending around the outside of the wringer post and having an opening 60 therein through which the handle 12 projects. It will be noted that with this construction the frame supporting the wringer and driving mechanism therefor is a 25 single casting having a shape chosen solely for its functional purposes. The shell 57, which comprises the rest of the wringer head, serves as an enclosure for the driving and supporting mechanism. The appearance or styling of the shell 57 30 may, therefore, be changed materially without changing the construction of the driving and supporting mechanism. This is a considerable advantage over the wringer constructions in general use wherein the driving and supporting mechanism is built into a wringer head which also serves as the enclosure for such mechanism. 35

On each side of the wringer are drainboards 40 61 having rounded upper edges 62 just below the bite of the wringer rolls and an inclined surface leading up to this edge which serves to guide the material to the rolls. The lower edges 63 of the drainboards are rounded and present a smooth surface so that the material being wrung will not be caught on the drainboard. 45

Between the side stiles are upper and lower wringer rolls 64 and 65. The lower wringer roll 65 is fixed to a shaft 66 having an integral coupling head 67. The coupling head has a pin 68 fixed therein which cooperates with slots 69 50 in the coupling member 32 to provide a driving connection between the shaft 28 and the lower wringer roll. At the other end the shaft 66 is journaled in a bearing 70 which is carried in a square bearing block 71, seated in a seat 72 integral with the side stile 2. The seat 72 is open at its upper end. 55

The upper wringer roll 64 is journaled on a shaft 73 which is fixed respectively at each end to depending arms 74 and 75. The shaft 73 and arms 74 and 75 serve as a carrier for the upper roll. Extending across the top of the wringer and freely pivoted at each end on the shaft 73 is a control bar 76. The control bar is provided at its center with a hand grip 77. The body of 60 the control bar is channel-shaped, the flanges 78 thereof being presented toward the upper roll (Fig. 4). Integral with the carrier arms 74 and 75 are ratchet members 79 (Fig. 6) having notches 80 cooperating with pawls 81 pivoted on 65 pins 82 fixed in the ends of the control bar 76 and urged toward the notches 80 by a leaf spring 83 arranged between the pawls 81 and pins 84 fixed in the control bar. Loosely pivoted on each 70 end of the shaft 73 is a guide plate 85 having a 75

slot 86 fitting over a pin-like projection 87 on cover plates 88 secured to the ends of the side stiles 1 and 2. The control bar is resiliently centered with respect to the guide plates 85 by wire springs 89 having ends 90 fixed to the plates 88 and the intermediate portions fixed to pins 91 on the control bar. Pivotal movement of the control bar with respect to ratchet members 79 is limited by flanges 92 on the ratchet members. 10 The guide plates 85 are spaced from the ends of the control bar by spacers 93.

The upper roll and the control bar and associated parts constitute a unitary assembly which can be inserted and removed as a unit. The 15 arms 74 and 75 have bosses 93 which fit in slots 94 in vertically slidable plates 95 carried in the inner faces of the side stiles 1 and 2 (Figs. 2 and 5). At the upper end of the slots 94 are hook shaped portions 96 which prevent direct upward 20 movement of the control bar assembly. To insert or remove the control bar, the control bar is tilted so that the bosses 93 extend angularly beneath the hook shaped portions 96. The openings provided by the hooked portions 96 are 25 covered by plates 97 hinged at 97a to the side stiles 1 and 2.

The lower ends of the plates 95 have openings 98 through which the bottom frame member 3 extends. A pair of leaf springs 99, one of which 30 bears against the lower side of the bottom frame member 3 and the other of which is hooked through the openings 98 bias the plates 95 downward. It will be noted that the force exerted by the springs in the frame is close to the side stiles. 35 There is, therefore, very little danger of distorting the frame due to the spring forces. If the upper spring were omitted, the force exerted on the bottom frame member 3 would be at its center. There would then be some danger of 40 flexing the bottom frame member and thereby causing spreading of the upper ends of the side stiles. The downward movement of plates 95 is limited by stops 100 which are fixed to the upper side of the bottom frame member 3 and 45 which engage the upper edges of the openings 98. Upward movement of the plates 87 is limited by the tension of the leaf springs 90. The plates 95 are provided with clearance openings 101 around the lower wringer roll shaft 66. The 50 plates 95 are enclosed by the cover plates 88 fixed respectively to the side stiles 1 and 2.

The slots 94 in the plates 95 have a central portion 102 in which the lower ends of the bosses 93 loosely rest and branched cam surfaces 103 on each side thereof which cooperate with rollers 104 journaled on shafts 105 fixed in the projections 106 and ratchet members 79. When the arms 74 and 75 are in the neutral position, shown in Fig. 7, the rollers 104 are directly above the bosses 93 and the control bar assembly is accordingly loosely carried in the slots 94. Under these conditions, the plates 95 are urged downward against the stops 100 by the leaf springs 99.

To apply pressure between the rolls the control bar is tilted to one side or the other of the central position, or in other words, toward or away from the operator. The arms 74 and 75 are tilted with the control bar by the pawls 81. During the tilting of arms 74 and 75 the rollers 70 104 cooperate with the cam surfaces 103 to force the upper roll against the lower roll. The plates 95 yield upward against the tension of the springs 99 limiting the pressure between the rolls. In the position shown in Fig. 8, the rollers 104 rest 75 in arcuate portions 107 and the direction of the

pressure is such that the rollers are held in this position. The upward pressure exerted on the upper roll is transmitted solely through the rollers 104 to the plates 95. The portions 102 of the slots 94 merely serve to limit the sidewise movement of the bosses 93. As varying thicknesses of material are fed between the rolls, the upper roll is forced upward, moving the control bar and plates 95 upward while the parts remain in the same relative position. As the control bar approaches the position, shown in Fig. 8, one of the pawls 81 is lifted out of its notch in the ratchet member by engagement with the upper end of the guide plate 85. This breaks the connection between the control bar and the arms 74 and 75 and permits the control bar to be returned upon release by the operator to the position shown in Fig. 9 by the springs 89. Since the arms 74 and 75 remain in the position shown in Fig. 8, the roll pressure is not released.

To release the roll pressure, the control bar is moved to the left, as viewed in Fig. 9, striking one of the flanges 92 on the ratchet members 79 and pivoting the arms 74 and 75 in a counter-clockwise direction. This returns the arms 74 and 75 to the neutral position of Fig. 7 and releases the roll pressure. At the conclusion of this movement, the control bar is released and is returned to the central position by the springs 89 and the connection between the control bar and the arms 74 and 75 is reestablished by the engagement of the pawls 81 with the notches 80.

The roll pressure is applied by tilting the upper roll carrier (arms 74 and 75 and shaft 73) to either side of the neutral or central position 35 and is released by returning the carrier to the neutral position. These operations are effected by tilting the control bar, there being a breakable connection between the control bar and the roll carrier so that the control bar is returned 40 to the central position after each operation. In the central position, the control bar is out of the operator's way. Also the pressure applied to the control bar to release the wringer pressure is applied with greater leverage. A horizontal force 45 applied to the hand grip 77 with the control bar in the position of Fig. 8 would be about two thirds as effective as the same force applied to the hand grip 77 with the control bar in the position of Fig. 7.

It will be noted that the movement of the upper roll is in a vertical direction while pressure is being applied and released since it is confined by the slots 102. Also, when the rolls are pressed together the angular position of the arms 74 and 75 is independent of the position of the plates 95. It is, therefore, impossible to release the roll pressure by wringing too great a thickness of material. This is due to the fact that in the wringing the arms 74 and 75 are wedged across 60 the slots 102 and the cam surfaces 107, both of which are part of the plates 95.

The tilting movement of the upper roll carrier is used to apply pressure between the wringing rolls and is also used to control the driving connection to the lower wringer roll. This is effected by means of an arm 108 projecting from the lower end of the arm 74 and having a projection 109 which fits in a channel shaped slot 110 (Fig. 5) in the part 53 of the slide 51. The channel shaped portion is enlarged at its upper end to facilitate insertion of the projection 109 therein when the control bar and upper roll assembly are being inserted in the wringer. It is obvious that 75

as the upper roll carrier is tilted, the slide 51 will be moved in the slot 52. As explained above, this movement of the slide controls the driving connection to the shaft 28. When the control bar 5 is in the central position the slide 51 will be in the center of the slot 52. The parts are designed so that when the upper roll carrier is tilted toward the operator the wringer rolls are rotated in the direction to wring material from the side 10 facing the operator.

Since the operation of the wringer is effected by moving the upper roll carrier to one side of the central position, it is desirable that accidental movement of the roll carrier to the operative position be prevented. This is effected by means of a projection 111 on the lower end of the arm 75 which cooperates with a groove 112 in a strip spring 113 secured to side stile 2. This serves as a detent holding the roll carrier in the 15 central position. The upper edge of the spring 113 is chamfered at 114 to facilitate insertion of the control bar assembly. The centering of the roll carrier is also effected by arched strip springs 115 fixed to pins 116 on guide plates 85. The 20 springs bear against the under side of ratchet members 79. When the roll carrier is in the central position, the springs 115 fit in depressions 117. When the roll carrier is tilted, the springs 115 are compressed as shown in Figs. 8 and 9.

30 What I claim as new and desire to secure by Letters Patent of the United States is:

1. In a wringer, a lower roll, an upper roll, pressure members for pressing the upper roll against the lower roll, a carrier for the upper roll 35 normally having a central position in which the roll pressure is released and engageable with said pressure members upon movement therefrom to apply the roll pressure, a handle on and movable relative to said carrier normally having a central position, means biasing the handle to its central position, means effective when the handle is in its central position for connecting the handle and carrier whereby the carrier is moved by the handle to apply and release the roll pressure upon movement of the handle from its central 40 position, means effective when the handle is in its central position for connecting the handle and carrier whereby the carrier is moved by the handle to apply and release the roll pressure upon movement of the handle from its central position, and means effective when the handle is away from its central position for breaking the connection between the handle and carrier whereby the handle is returned to its central position without moving the carrier upon release by the operator.

2. In a wringer, a lower roll, an upper roll, a carrier for the upper roll normally having a central position in which the roll pressure is released, means effective upon movement of the carrier from its central position for applying the roll pressure, a handle on and movable relative to the carrier having a central position, means biasing the handle to its central position, means effective when the handle is in its central position for connecting the handle and carrier whereby the carrier is moved to apply and release the roll 55

pressure upon movement of the handle from its central position, and means effective when the handle is away from its central position for breaking the connection between the handle and carrier whereby the handle is returned by said biasing means to its central position without moving the carrier upon release by the operator. 5

3. In a wringer, a lower roll, an upper roll, a carrier for the upper roll normally having a central position in which the roll pressure is released, 10 means effective upon movement of the carrier from its central position for applying the roll pressure, a handle on and movable relative to the carrier having a central position, means biasing the handle to its central position, and a 15 connection between the handle and the carrier whereby the carrier is moved to apply and release the roll pressure upon movement of the handle from its central position, said connection having sufficient lost motion so that the handle is 20 returned to its central position by the biasing means without moving the carrier upon release by the operator.

4. In a wringer, a frame having a roll therein, 25 receivers resiliently mounted on said frame, another roll, a carrier therefor receivable in said receivers for pivotal movement therein, said carrier having a normal position in said receivers in which the carrier is free to move relative to the receivers toward and away from the first 30 roll, means engageable by said carrier upon pivotal movement from said normal position for holding the carrier in fixed relation to the receivers, a handle on and movable relative to said carrier for pivotally moving the carrier, means biasing the handle to a central position, and a connection 35 between the handle and carrier whereby the carrier is moved toward and away from its normal position upon movement of the handle from its central position, said connection having sufficient 40 lost motion so that the handle is returned to its central position by the biasing means without moving the carrier upon release by the operator.

5. In a wringer, a frame having a roll therein, 45 receivers resiliently mounted on said frame, another roll, a carrier therefor receivable in said receivers for pivotal movement therein, said carrier having a normal position in said receivers in which the carrier is free to move relative to the receivers toward and away from the first 50 roll, means engageable by said carrier upon pivotal movement from said normal position for holding the carrier in fixed relation to the receivers, a handle on and movable relative to the carrier, and connections between the handle and carrier 55 whereby the carrier is moved upon movement of the handle from its normal position and is not moved upon return of the handle to its normal position.

GEORGE J. FILIA. 60
